John P. Gidos, P.O. Box 205, Ludlow, Pa. 16333

Filed Oct. 24, 1973, Ser. No. 409,156

Term of patent 14 years

Int. Cl. D19—02

U.S. Cl. D19—77

FIG. 1 is a perspective view of a holder for clerical articles or the like, showing my new design;

FIG. 2 is a front elevational view thereof, the top horizontal member being omitted for ease of illustration;

FIG. 3 is a cross-sectional view taken along 3-3 of FIG. 2;

FIG. 4 is a front elevational view of a modified form of the holder for clerical articles or the like, the top horizontal member as shown in FIG. 1 being omitted for ease of illustration; and

FIG. 5 is an enlarged scale fragmentary right side elevational view taken along line 5-5 of FIG. 4.

I claim:

The ornamental design for a holder for clerical articles or the like, as shown and described.
